Adam Hampton. Design for a Grateframe and Summer-piece.

Dec. 507

Adam Hampton of New York, N.Y.
Letters Patent No. 507 Dated Oct. 5th 1852

The schedule referred to in these Letters Patent and making part of the same

To all whom it may concern:

Be it known that I, Adam Hampton, of the City, County, and State of New York, have invented or produced, a new & original design for a "Grate frame and Summertime," and I do hereby declare the following to be a full, clear and exact description of the same reference being had to the accompanying drawing, representing one half of the configuration in full - the other half which is precisely similar in outline only.

The frame is cast in two pieces, the back part being formed of two plain broad cavello mouldings a b: - the outer one a, terminating in a delicate sunken moulding c, and the inner one b, in a raised bead moulding d, both of which extend entirely around the frame on its outer and inner margins. The general outline of the frame is formed of perpendicular jambs and a semi-elliptical top. The front part of the frame upon which the ornaments are principally placed, has a base e, upon which rests a foliated scroll f. From the top of which rises a long stem g, which meets a foliated bracket h, connecting the base

with the prominent ornament which decorates the centre of the top of the frame. Where the stem g; and bracket h, meet, there is a deeply indented leaf i, on the outer side, & flowers j, with leaves and a vine pendant, on the inner side or underneath their volutes. The centre piece k, is made up of foliated volutes, flanked with flowers & leaves l, & surmounted by a foliated scroll or bracket m. The inner margin of the front part of the frame, is ornamented with a stem n, entwined with foliated scroll work o, & voluted brackets p, which connect the outer and inner ornaments together. The ornaments generally are in alto-relievo, and are upon open grounds.

The centre of the summer-piece, is a low sunken panel, the prominent ornament being a fruit piece q, surrounded with foliated scroll work upon open ground, and is connected to the outer part by highly wrought mouldings r, outside of which is scrollwork terminating in foliage with open latticed and plain ground, the whole forming a design in the Elizabethian style, difficult to describe, but fully represented in the accompanying drawings.

The red line x, represents a section through the frame, which shows the height of the various parts.

Having thus fully described the nature of my design what I claim therein as new and desire to secure by Letters Patent is the combination and arrangement of the ornamental figures herein represented, the whole forming an ornamental design for a grate frame and summer piece.
